UNITED STATES PATENT OFFICE

JOHN J. CAMPODONICO, OF STOCKTON, CALIFORNIA, ASSIGNOR TO SERAFINO PAULINO, OF TIBURON, CALIFORNIA, AND MODESTO E. ESPOSTO, OF SAN FRANCISCO, CALIFORNIA, AS JOINT TENANTS

TRACTION WHEEL

Application filed May 23, 1927. Serial No. 193,427.

This invention relates to traction wheels of the type shown in my former patent entitled Traction wheel, Number 1,370,409, issued March 1st, 1921, and particularly to improvements on the link connections formed between the shoes and the wheel.

In the form of structure shown in the patent, above referred to, two links were required in connection with each shoe, one link would be placed in tension and form the driving connection between the wheel and the shoe when driving ahead and vice versa the other link would be placed under compression when the wheel was reversed. This arrangement, of course, doubled the number of links required, it increased weight, wear and tear and the cost of manufacture and repairs. The links were, furthermore, spaced apart and disposed one on each side of the shoe. This was also found to be detrimental as a twisting movement or side-thrust was created when driving, which further increased wear.

The object of the present invention is to generally improve and simplify the construction and operation of the link connections of the character described; to provide a single link between the wheel and shoe, so connected that it may be placed in tension or compression and as such will serve as a driving connection when driving ahead or reverse; to provide a link connection which will positively prevent slippage between the wheel and the shoes and further to provide a link connection in which twisting space or side-thrust is entirely eliminated.

One form which the invention may assume is shown by way of illustration in the accompanying drawings, in which:—

Figure 1 is a sectional view of a portion of a traction wheel showing the application of the shoes,

Figure 2 is a cross section taken on the line II—II of Figure 1.

Figure 3 is a sectional view similar to Figure 1, but showing a modified form of link connection,

Figure 4 is a similar section of Figure 1, showing another modified form of link connection,

Figure 5 is a diagrammatic view showing

the form of link connection illustrated in Figure 1,

Figure 6 is a diagrammatic view showing the form of link connection illustrated in Figure 3.

By referring to the drawings and particularly Figures 1 and 2, it will be noted that only a portion of the rim of a traction wheel is illustrated. This is due to the fact that any standard form of hub structure, spokes, etc., may be employed. The rim is, in this instance, indicated at A and it is supported by a circular disc B in the manner of disc wheels. Secured on the exterior periphery of the rim are continuous annular flanges as indicated at 2, 3, 4 and 5 and held in engagement with the flanges are a plurality of shoes generally indicated at C.

These shoes form a flexible track for the wheel whether it rotates ahead or reverse and the invention, in this instance, is particularly directed to the driving connections formed between the rim and the shoes. The shoes are elongated and are rectangular in shape. They are all identical in construction and the description of one shoe and its connection with relation to the rim of the traction wheel should, accordingly, suffice. The shoe consists of a tread section 6 on the outer face of which is formed grousers or like flanges such as indicated at 7 and 8. On the inner surface are formed a pair of track members 9 and 10 and intermediate the track members are formed segmental sections, such as indicated at 11 and 12.

These segmental end sections are disposed at opposite ends of the shoe and they project upwardly or inwardly through the rim, openings such as indicated at 14 and 15, being formed in the rim to receive the segmental sections. The segmental end sections are shown in my former patent referred to and serve the function first of limiting the rocking movement of the shoe with relation to the flanges 2, 3, 4 and 5 and secondly of securing the shoe against twisting or lateral movement so that alignment will be maintained between the flanges and the track members 9 and 10.

Extending cross-wise of the shoe, inter-

mediate the segmental end section 12 is a cross pin 16 and pivotally connected therewith is a link 17. Secured to the rim of the wheel or formed integral therewith is a pair of inter-spaced lugs 18 and secured between said lugs 5 is a pin 19, to which the opposite end of the link is connected. The link forms a driving connection between the rim and the shoe whether the wheel is travelling ahead or reverse and as such is placed under tension 10 when driving in one direction and under pressure when reversing. The link permits a rocking movement of the shoe with relation to the rim or as stated in another manner will assume a horizontal position as shown in 15 Figure 1, while the wheel is travelling over the same. The shoe is also provided with a pair of centrally disposed interspaced lugs 20 through which passes a cross pin 21. Pivotally attached to this cross pin is a bolt 22. This bolt extends radially inwardly 20 through an opening 23 in the rim and its innermost end is provided with a plate 24 and a nut 25. 25 A spring 26 is interposed between the inner surface of the rim and the plate 24 and the bolt together with the spring serves the function of normally maintaining the shoe in engagement with the rim. 30 The method of connecting the link 17 with relation to the shoe and the rim forms an important feature of the present invention, as elongation or contraction of the link cannot take place during rocking movement 35 of the shoe, with relation to the rim or when a horizontal position is assumed by the shoe when the rim is rolling over the same. A particular method of making the link connection is, perhaps, best illustrated in Figure 5. The length of the track portion of the 40 shoe will, for the purpose of illustration and description be assumed as being one foot as shown in Figure 5. If this is the case, the length of the link will also have to be one foot, and the connection between the link and the rim will have to be at a point where 45 the circumferential distance from the point indicated at 28 to the point indicated at 29 will equal one foot. 50 It will also be essential that the center of the link pivot 19 shall be on the line of contact between the flange of the rim and the rail surface of the shoe and that the opposite link connection which is made at 16 shall be at a point below the point of contact 55 between the rail and the flange section of the wheel, the pivotal point 16 being found by taking a compass and placing it at the first of the point 29 and striking the line 30 and 60 then placing the compass at the point 31 and striking a second arc which is shown at 32. Where these two arcs intersect, the pivotal points 16 will be placed. With the link connected in this manner and where the specified 65 lengths are maintained, free rocking move-

ment of the shoe with relation to the rim is permitted without contracting or elongating the link and without throwing any shearing strain on the pivotal connections 16 and 19. The pivotal connections may also be made as 70 shown in Figure 6 by placing the pivotal connection with the shoe such as shown at 16 on the line of contact between the rim flange and the rail of the shoe and by connecting the opposite end of the link at a point above 75 the line of contact between the wheel flange and the rail, as shown at 33 in Figure 6.

Again, it is possible to place one pivot slightly below the line of contact between the wheel flange and the rail and the other 80 pivotal connection slightly above or vice versa as shown in Figure 4 of the drawings. The important feature which must be maintained is equal lengths of the members as already described, as any variation in any one 85 of the three dimensions will necessitate contraction or expansion of the link with a consequent shearing strain on the pivotal end connections.

By connecting the link, as described and 90 by placing it centrally of the shoe, a single link will serve the same purpose as the pair of links described in my former patent. This lessens the number of links by one-half and it furthermore entirely eliminates any side 95 or twisting strain when the wheel is in operation as the pull or pressure exerted whether travelling ahead or reverse will be directed to the center of the shoe due to the central position of the link between the rail members 100 9 and 10.

While certain features of the present invention are more or less specifically described, I wish it understood that various changes may be restored to within the scope 105 of the appended claims. Similarly that the materials and finishes of the several parts employed may be such as the manufacturer may decide or varying conditions or uses may demand.

Having thus described my invention, what I claim and desire to secure by Letters Patent is:—

1. In a traction wheel of the character described, a rim section, a pair of annular inter-spaced flange rings thereon, a shoe exterior of the rim, interspaced track members on the shoe aligning with and engaging the ring flanges on the rim, a single driving link between the shoe and the rim, a pivotal connection between one end of the link and the rim, a pivotal connection between the opposite end of the link and the shoe, said pivotal connection at one end of the link having its center on the line of contact between the 115 ring flanges and the track surfaces on the shoe and the opposite pivotal connection being made at one side of said line of contact.

2. In a traction wheel of the character described, a rim section, a pair of annular in-

terspaced flange rings thereon, a shoe exterior of the rim, interspaced track members on the shoe aligning with and engaging the ring flanges on the rim, a single driving link between the shoe and the rim, a pivotal connection

5 between one end of the link and the rim, said pivotal connection having its center on the line of contact between the ring flanges and the track surfaces on the shoe, and a pivotal connection between the opposite 10 end of the link and the shoe, said pivotal connection being made at a point exterior of said line of contact.

3. In a traction wheel of the character described, a rim section, a pair of annular interspaced flange rings thereon, a shoe exterior 15 of the rim, interspaced track members on the shoe aligning with and engaging the ring flanges on the rim, a driving link between the shoe and the rim, a pivotal connection 20 between one end of the link and the rim, said pivotal connection having its center on the line of contact between the ring flanges and the track surfaces on the shoe, a pivotal connection between the opposite end of the 25 link and the shoe, said pivotal connection being made at a point exterior of said line of contact, and spring actuated means normally maintaining the shoe in contact with the ring flanges.

4. In a traction wheel of the character described, a rim section, a pair of annular interspaced flange rings thereon, a shoe exterior 30 of the rim, interspaced track members on the shoe aligning with and engaging the ring flanges on the rim, a single driving link between the shoe and the rim, a pivotal connection between one end of the link and the rim, a pivotal connection between the opposite end of the link and the shoe, said pivotal 35 connection at one end of the link having its center on the line of contact between the ring flanges and the track surfaces on the shoe and the opposite pivotal connection being made at one side of said line of contact, 40 said link and track members on the shoe having an equal length, and the length of the link and track sections on the shoe being equal to the length of the line of contact between the ring flanges and the track members.

JOHN J. CAMPODONICO.
